UNITED STATES PATENT OFFICE.

ALVA L. KITSELMAN, OF RENO, NEVADA.

WIRE-FENCE MACHINE.

1,047,078.

Specification of Letters Patent. Patented Dec. 10, 1912.

Application filed October 24, 1910. Serial No. 588,741.

To all whom it may concern:

Be it known that I, ALVA L. KITSELMAN, a citizen of the United States, residing at Reno, in the county of Washoe and State of Nevada, have invented certain new and useful Improvements in Wire-Fence Machines, of which the following is a specification.

This invention has reference to certain new and useful improvements in wire-fence machines, particularly to that type employed for the manufacture of a "square-mesh" fencing, composed of a plurality of running or longitudinal wires connected by transverse stay wires. In this instance the stays are united or connected to the longitudinal or running wires by forming loops in the bodies of the stays where they coincide with the intermediate running wires and wrapping or coiling said loops around said running wires; the ends of the stays being preferably connected to the outside running or selvage wires by wrapping or coiling the plain ends of the stays around said selvage wires.

25 The object of the present invention is to embody in a machine employing a single stay-wire feed, wire-connecting mechanisms for simultaneously making two widths or two rolls of fencing; and it is accomplished, 30 by feeding the required length of stay-wire to said connecting mechanisms and operating such mechanisms in a manner to draw in the surplus amount of wire for forming a union between the stay and longitudinal 35 wires, from opposite ends of said stay-wire, and severing the stay-wire intermediate its ends into two stay-lengths and wrapping or coiling the ends of said stay-lengths around corresponding marginal or selvage-wires of 40 the respective widths or rolls of fencing.

A fence such as is capable of being made by my machine is not new with me. That is to say: I am not the first to have made a machine for uniting stays to longitudinal 45 wires, where loops were formed in the stays and such loops coiled or wrapped around the longitudinal wires. One type of machine for manufacturing such a fence included combined loopers and coilers and a 50 reciprocating needle which fed the stay-wire from coiler to coiler, from which a stay was severed after each operation of placing the stay-wire across the wires forming the fence and uniting such stay-wire to adjoining longitudinal wires; a second type comprised a machine where the stays had their

loops formed on a separate machine and such "looped stays" transferred or deposited on the coilers to have the loops coiled about the strand wires for uniting the fence wires; and a third type, a machine where the stay-wire is projected endwise across the several longitudinal wires by a suitable feed and from such stay-wire is severed a stay-length. This stay-length is then moved laterally and deposited on combined loopers and coilers, and during the looping and coiling operation the stay-wire is being projected endwise across the longitudinal wires and moved laterally, whereby the successively fed stay-lengths are attached to said longitudinal wires. In this last-mentioned machine the looping and coiling operation begins at the center coilers and continues toward the opposite or selvage coilers drawing in the surplus wire from the opposite ends of the stay-length. Thus the capacity of the machine is greatly increased on account of its taking so little time to feed and attach a stay. In fact, it is safe to say that with such a machine approximately twice as many stays could be attached in the same time as had previously been accomplished, but in neither of these machines is there shown or employed a single stay-wire feed from which is severed a stay-length and such stay-length united to a plurality of wires forming two rolls or widths of fence simultaneously. Therefore, the present machine has considerable advantage over the known art, in that its capacity has been greatly increased, and the fact that it is capable of manufacturing two widths or rolls of fence simultaneously, using only a single stay-wire feed, renders more effective the operation of the machine. It is to be observed, however, that the machine is not limited to the manufacture of two rolls which shall be of the same width, as may be supposed, but such rolls may be of different widths. For instance in Fig. 2, which is a diagrammatic plan view of the loopers and coilers, two rolls could be made approximately 26" in width, or one made 26" in width and the other 32" in width. This is accomplished by adding one more coiler to the left-hand series and using the same or not as may be desired, of course regulating the stay-wire feed to bring about such a result.

That the invention may be more fully understood, reference is had to the accom-

panying drawings, forming a part of the specification, in which:

Figure 1 is a front elevation of only so much of my machine as is necessary to illustrate the application of my invention thereto; Fig. 2 is a diagrammatic plan view of a double series of loopers and coilers, showing the relative arrangement and spacing of such coilers, making it possible to manufacture two widths or rolls of fence simultaneously. The view also shows a variable number of coilers in the two series, whereby a roll of fence of one width may be made by one series of coilers and a roll of a different width may be made by the other series of coilers simultaneously; Fig. 3 is a plan view of a portion of the front part of the machine, shown in Fig. 1; Fig. 4 is a vertical section of the machine with the frame-work and most of the operating connections omitted; Fig. 5 is a vertical sectional view similar to Fig. 4, except that the section is taken at a point central of the machine to show the center cutter for severing the stay-wire into two separate stay-lengths; Fig. 6 is a plan view of a section of the front portion of the machine, showing the positions assumed by certain of the parts during the feeding of the stay-wire across the series of line wires; Fig. 7 is a similar view, showing the parts shifted, including the movable cutter for severing the stay-length from the stay-wire, which said parts also move the severed stay-length laterally into position to be connected to the longitudinal wires; Fig. 8 is a similar view, showing the parts returned to normal position with the stay-length held in place and ready to be applied to the longitudinal wires; Fig. 9 is a section, as the same would appear on the line 9—9 of Fig. 3; Fig. 10 is a diagrammatic plan, showing in dotted lines, a number of the coilers of the two series, and a stay-length; also showing in what order the coilers of the two series are operated to start the looping and attaching of the stay-length to the longitudinal wires of the two widths of fence; Fig. 11 is a view similar to Fig. 10, but shows the second step in the operation of the coilers; Fig. 12 is a view similar to Figs. 10 and 11, but shows the third step in the operation of the coilers. In this view the center cutter which severs the stay-length into two sections, has been operated to sever such stay-length, however, the cutter may be timed to operate at any time after the operation which has taken place in Fig. 10, as it is necessary to place a tension on the stay-length to facilitate in making a tight wrap of the inner severed ends around what will be the top and bottom selvage or marginal wires of the two widths of fence.

Like characters of reference denote corresponding parts throughout the figures.

65 I have not attempted to detail or even

outline the structural or frame parts for supporting the operating mechanisms of the machine, as it may be of any suitable character for the purposes herein; nor do I detail the power mechanisms which would ordinarily be associated with the operating mechanisms, as these too may be of any suitable character and applied and assembled in any suitable manner to accomplish the result described and aimed at herein.

1 designates a horizontal bed-plate or table, which is provided with a plurality of openings 2. These openings are arranged in two series, referred to as the "right series" and the "left series." For convenience the "right series" numbers seven (7) openings and the "left series" numbers eight (8) openings, and such openings 2 constitute coiler sockets, within which are mounted to rotate revoluble coiler heads 3, see Figs. 4 and 5. The coiler heads 3, as well as the openings 2 of the two series are arranged in line with one another, as shown in Figs. 2 and 3; and the intervals between the adjacent coilers of the two series are graduated from one end of the series to the other, in accordance with the gradually increasing intervals between the line wires of the fence, which, as is well understood in the art, are separated by progressively increasing intervals from the lower to the upper edge of the fence. In the present showing, referring to the "right series" of coilers, the intervals between the coilers gradually increases, beginning with the outside or end coiler at 100. the right-hand end of such series, while the intervals between the coilers of the "left series" gradually increases, beginning with the inner or end coiler at the right-hand end of such series; or in other words, the coiler for the selvage or marginal wire for the top of the fence of the right-hand roll of fence, adjoins the coiler for the selvage or marginal wire for the bottom of the fence of the left-hand roll of fence, see Fig. 2. For convenience, I have indicated the individual coilers of the respective "right" and "left" series by the characters *a*, *b*, *c*, *d*, *e*, *f*, and *g* and an additional coiler of the "left" series as *h*, indicating the sequence of operation of the coilers of each series, and also indicating the corresponding coilers of the two series which work in pairs, since both series of coilers are in operation at the same time.

It will be observed that the coiling operation does not begin with the innermost coilers "g," "g" of the two series, but that the coilers "a," "a" of the respective "right" and "left" series are first started, see Fig. 10, and just after such coilers have been rotated sufficiently to produce loops *i* in the stay-length *j*, the coilers "b," "b" of the two series will come into operation, and just after such coilers have been rotated sufficiently to 130

produce loops *i*, in the stay-length *j*, the coilers "c," "c" will come into operation. This operation is continued until each and all of the corresponding coilers "d," "e," and "f" have been operated, when the coilers "g," "g" of the two series will come into action and complete the stay attaching operation by coiling the ends of the respective stay-sections around the top and bottom wires of the respective rolls of fence, only however, after the stay-length has been severed into two stay-sections in a manner which will be explained.

The "left series" of coilers includes one more coiler than is shown in the "right series," the object of which is to produce a machine capable of making two rolls of fence of a similar width, or two rolls of varying width. By changing the coiler "f" from a looper to an end coiler and cutting out the coiler "h" the present machine could be used to manufacture two widths of fence approximately 26" in width, whereas, if the coiler "f" is left as a looper and the coiler "h" as an end coiler, the machine could be used to manufacture two widths of fence, one approximately 26" in width and the other approximately 32" in width. The two coilers "g," "g" of the respective "right" and "left" series are timed to operate coincident with or just after starting the coilers "f" of the two series, but it is to be understood that the coilers "g," "g" may be brought into action any time after the looping operation by the coilers "a," "a" which is necessary to place a tension on the two severed stay-sections of the stay-length, otherwise, if the stay-length was severed between the coilers "g," "g" before the operation of looping or attaching any other part of the stay-sections, it would be impossible to make a proper wrap of the inner ends of the respective stay-sections around the marginal or selvage wires. The means of severing the stay-length *j*, from the stay-wire will be described.

The top portion of each coiler head 3 is in the form of a detachable plate or disk 4 suitably secured to said head 3 and having its upper surface flush with the surface of the table or bed plate 1, see Fig. 4. The plate 4 is formed with a segmental opening 5, see Fig. 3, the divergent walls 6 and 7 of which are tangential to a circle concentric with the axis of the coiler and somewhat greater in diameter than the diameter of the longitudinal wires. This construction of the plate 4, constituting an element of the coiler head, produces in effect a head having in the upper surface thereof a segmental recess having the axis of the head located within its confines and disposed adjacent to the juncture of the convergent walls of said recess. The wall 7 of the opening or recess 5 is undercut, as

shown in dotted lines in Figs. 3 and 6. This undercut edge of the opening therefore defines what may be termed a loop-depressing cam 8 designed to ride over and depress the looped portion of the stay to facilitate in said loop being coiled or wrapped around its coinciding longitudinal wire.

Dependent from and preferably integral with the coiler 3 is a hollow spindle 9, journaled in suitable frame parts, and allowed to rotate but preferably held against longitudinal movement. Immediately below the coiler head 3 is disposed a collar 10 encircling the spindle 9 and arranged to be reciprocated thereon for the purpose of lifting or depressing the stay looping or coiling pin 11, into or out of operative position. I refer generally to the pin as 11; if it is an end coiler it has a hook 12, but if the pin is a looper, the hook 12 is omitted. The pin 11 is secured to the collar 10, and normally projects upwardly through the coiler head 3 at a point within the confines of the opening 5 somewhat in advance of the wall 7 and closely adjacent to the outer wall of the opening. The upper extremity of the pin normally projects above the upper surface of the plate 4, see Fig. 4, being retained in this position in a manner to be described. All of the combined loopers and coilers 3, with the exception of those at the ends of the "right" and "left" series, are identical in construction and mounting with the one just described, all of the heads 3 being mounted to rotate in the table or bed-plate 1. The end coilers are identical with the others, except as stated, the upper ends of their pins 11 are laterally deflected or hooked to better engage the end portions of the respective stay-sections.

The mechanism for actuating the coilers is such that they will be operated in series, or in other words, the operation of corresponding coilers of the "right" and "left" series will be simultaneous, while the successive coilers of each series will be brought into action successively, without, however, allowing the preceding coilers of each series to complete their operation before the operation of the next coilers is inaugurated. Thus, while the corresponding coilers of the two series will be the only ones operating in complete coincidence, several or all of the coilers of both series may be operating at the same time, since the last coilers of said series may come into action before the first coilers thereof have completed their operation, whether this is true or not, depending, of course, upon the number of coilers embraced by each series.

Carried on the lower ends of the spindles 9 are bevel pinions 13, and said pinions 13 are in mesh with and adapted to be driven by similar pinions 14 carried on transversely disposed short shafts 15 journaled in suitable

frame parts, and on the inner ends of said shafts 15 are carried bevel pinions 16 having hubs 17 adapted to have a locking relation with segmental driving gears 18. These 5 gears 18 are carried on an operating shaft 19 which may receive its power from any suitable source and in any suitable manner. There are approximately thirty-five teeth 20 on each segment gear 18, and each pinion 16 10 has approximately twelve teeth, therefore, with each revolution of the shaft 19, the shafts 15 will rotate approximately three times, and the spindles 9 will be rotated a like number of times. Each gear 18 has 15 a segmental locking flange 21 terminating at the opposite ends of the teeth 20. For a given period, during the rotation of shaft 19, it will be observed that the gears 18 and pinions 16 will be in mesh and cause the 20 operation of the spindles 9, and during the remaining period of such movement, the spindles 9 will remain at rest and held against rotation by the engagement of the locking flange 21 with the hubs 17 of pinions 16, said hubs being suitably constructed 25 to bring about such a result.

To operate the coilers in the directions indicated by the arrows in Fig. 2, I arrange the gears 18 for the respective coilers as 30 follows, see Fig. 1: Referring to the "right series" all the gears 18 with the exception of the gear for operating the coiler "g" for the top selvage or marginal wire, face toward the right-hand side of the machine, 35 whereas, the gear for coiler "g" faces the left-hand side of the machine. Referring now to the "left series," I call attention to the fact that for the coilers "a" and "g," because of their being so close together, a 40 single gear 18 is provided having two sets of oppositely disposed teeth 20 and two oppositely disposed locking flanges 21. The teeth, however, for actuating all coilers of the "left series," with the exception of 45 coiler "g," face the left-hand side of the machine, whereas, the teeth for actuating coiler "g" face the right-hand side of the machine. Thus, the coilers of the "right series" and the coiler "g" of the "left series," excepting coiler "g" of the "right series," all rotate in the same general direction; while the coilers of the "left series" 50 and the coiler "g" of the "right series," excepting coiler "g" of the "left series," all 55 rotate in the same general direction, but in a direction opposite to the coilers of the "right" and "left" series just above referred to. It will also be observed, by reference to Fig. 1, that the several gears 18 of 60 each series are graduated as to their movements or periods of operation, the gears 18 for the coilers "a," "a" of the "right" and "left" series having the most advanced position and therefore coming into action first, 65 and the gears 18 for the coilers "f," "f" at

the outer end of each series and the gears 18 for the coilers "g," "g" at the inner ends of such series being the least advanced, come into action last, in manner and for purposes previously explained. 70

During the rotary movement of the coilers 3, their pins 11 are adapted to be withdrawn from their normal position, see Fig. 4, and subsequently restored to such position. To effect the performance of this 75 function at the proper time, a series of cam levers 22, see Fig. 4, are fulcrumed at the rear edge of the table or bed-plate 1 with their bifurcated front ends 23 engaging peripheral grooves 24 in the collars 10. The 80 rear ends of the levers 22 carry rollers 25 disposed in co-operative relation with two cams 26 and 27 suitably carried by or mounted on disks 28 keyed or otherwise secured to a cam shaft 29, suitably carried 85 in the machine frame and operated in any suitable manner. The cams 26 and 27 must be graduated to correspond with the graduation of the gears 18, for the reason, that the period of operation of each pin 11 with 90 respect to the period of rotation of its coiler head is the same, and therefore each cam must have the same relation to the corresponding gear 18. At a predetermined point in the rotary movement of the coiler, 95 its pin 11 is drawn down by the roller 25 of lever 22 riding over the cam 26 which will depress collar 10 and pin 11 on spindle 9. Immediately upon the roller 25 leaving cam 26 it rides under the cam 27 which will operate to force the lever 22 in the opposite direction and raise the collar 10 and pin 11. Normally, the pins 11 are located at the front side of the coilers, see Figs. 3 and 6. 100

Associated with each coiler and normally 105 located above the same is a presser foot 28, which may be of any suitable construction to perform the functions for which it is intended. Each presser foot is connected with or attached to a presser foot bar 29 110 disposed lengthwise of the table or bed-plate 1, at the rear edge thereof, see Fig. 3. The presser feet normally occupy the positions shown in Figs. 4 and 6, and assist in the wrapping or coiling of the stay 115 around the longitudinal wires. After the stays have been connected to the line wires, the presser feet are withdrawn rearwardly to the position shown in Fig. 7 in order to permit the longitudinal wires and the attached stay-sections to be advanced or elevated in order that the succeeding stay-sections may be applied, the presser feet being then returned to normal position to aid in the application of said succeeding stay-sections. 120

Extending across the table or bed-plate 1 adjacent to the front side thereof is a stay-wire-table 30, Figs. 3, 6, 7, 8 and 9, the upper surface of which is flush with or slightly 125

above the upper ends of the pins 11 when the latter are in their elevated positions. The rear edge 31 of the table 30 is located in rear of the positions occupied by the pins 11, see Fig. 3, to permit which the rear edge of the table is indented by arcuate recesses 32 concentric with and having a radius substantially equal to the radius of the adjacent coilers. Supported above the stay-wire-table 30 is a combined stay-wire guide and feed bar 33 connected to the presser foot bar 29 by end plates or straps 34, the bars 29 and 33 and the connecting end plates or straps 34 constituting a transversely reciprocal frame disposed above the table or bed-plate 1. In the underside of the stay-wire feed bar 33 is formed a stay-wire guide or groove 35, which, in the normal retracted position of the feed bar, is disposed opposite a stationary stay-wire guide 36 fixed to the table or bed-plate 1 beyond the right-hand end of the feed bar, see Fig. 3.

The stay-wire, which for convenience is referred to as *k*, may be fed from any suitable source, through the guide 37, thence between the feeding wheels 38 and 39 which have a predetermined movement and are adapted to feed in the stay-wire a sufficient distance so that there may be severed therefrom a stay-length, subsequently attached to the two sets of longitudinal wires *l*, and severed into two stay-sections. The stay-wire thence passes through the guide 36 and feed bar 33. The feed bar 33 is guided in its transverse movement by overhanging guides 40 secured at their front ends to the table or bed-plate 1 and engaging transverse grooves 41 in the feed bar. At the right-hand end of the feed bar 33 is disposed a stay-wire cutter 42 arranged to pass across the inner end face of guide 36 and thus sever the stay-length *j*, from the stay-wire *k*, as the bar 33 moves rearwardly to carry the stay-length to the coilers. The movement of the feed bar 33 and the presser feet 28 transversely of the table or bed-plate 1 is effected through the instrumentality of a rock-shaft 43, suitably supported and operated, said shaft being equipped with several arms 44 connected by links 45 to the bar 33. The operation of shaft 43 will, at the proper time move the arms 44 and links 45 and thus reciprocate the frame including the presser foot bar 29 and the stay-wire feed bar 33.

Extending forwardly from the presser foot bar 29 are tension members 46 adjustably secured to the bar by bolts 47 and having their front ends disposed opposite shallow notches or depressions 48 in the rear face of the stay-wire-table 30, see Fig. 3. These tension devices or bars 46 are designed to clamp the stay-wire against the rear face of the stay-wire-table for the purpose of placing the same under sufficient

tension to facilitate the operation of the coilers. Also associated with the table 30 are a plurality of stay-wire depressions 49, see Figs. 3 and 9, in the form of inclined blades carried at the rear ends of spring shanks 50, the front ends of which are curved back, as shown in Fig. 9, and bolted to the table or bed-plate 1. To accommodate the depressors 49 the stay-wire-table 30 and the feed bar 33 are provided at their rear edges with open ended slots or notches 51 and 52. The bottom face 53 of the depressors are slightly inclined from the horizontal in order that as the stay-wire is depressed it will also be urged forwardly into engagement with the front face of the table 30.

Reference will now be had to the cutter for severing the stay-length *j*, into two separate sections, each being connected to a distinct roll or width of fence: 54 denotes a cutter blade mounted to have a reciprocal movement on the table or bed-plate 1 beneath the presser foot bar 29 in a guide 55, located preferably between and adjacent the end coilers "g", "g" of the "right" and "left" series of coilers. The forward or cutting end of the cutter 54 cooperates with a stationary cutting member 56 seated in the rear edge of the table 30, see Fig. 3. The rear end of the cutter 54 has a pivotal connection with links 57 and said links have a pivotal connection with one end of a bell-crank lever 58 fulcrumed at 59 in a bracket 60 secured to the rear edge of the bed-plate 1. The opposite end of said bell-crank lever 58 carries a roller 58^a adapted to have a cooperative relation with cams 60^a and 61 carried by a disk 62 on the shaft 29. The cams 60^a and 61 are so disposed on the shaft 29^a that the cam 60^a will ride under the roller 58^a, approximately coincident with the operation of the inner end coilers "g", "g" of the respective "right" and "left" series of coilers, causing the cutter 54 to be moved forwardly severing the stay-length *j*, into two separate sections, see Fig. 12, and as the cam 60^a rides from beneath the roller 58^a, the cam 61 will ride over and engage roller 58^a returning the cutter 54 to inoperative position, seen in Fig. 3.

The longitudinal or running wires *l* which are fed through the coiling stems 9 may be led thereto in any suitable manner and from any suitable supply, and the completed stretches of fence may be directed away from the coiling devices by any suitable means.

What I claim is:

1. A wire fence machine, including two sets of wire connecting devices, the devices of each set adapted to be operated beginning with a device located at an intermediate point of each set, and certain of the devices of each set arranged to operate in

- coincidence; a single stay-wire feed for said sets of devices, a cutter to sever a stay-length from the stay-wire, and a cutter for severing said stay-length into two stay-
5 sections.
2. A wire fence machine, including two sets or series of wire connecting devices, the devices of the two sets or series arranged in line with one another, means for feeding a
10 stay-wire adapted to be operated on by all of said devices, means for severing a stay-length from said stay-wire, and a cutter for severing the stay-length into two stay-sections.
- 15 3. A wire fence machine, including two sets or series of wire connecting devices, one set comprising an even number of such devices, and the other set comprising an odd number of such devices, a single stay-wire
20 feed for the two sets of devices, means for severing a stay-length from the stay-wire, and means for severing the stay-length into two stay-sections.
4. A wire fence machine, including two sets or series of wire connecting devices for manufacturing two widths or rolls of fence simultaneously, a single means for projecting a stay-wire across said two sets of devices, means for severing a stay-length from
25 said stay-wire, means for operating certain of the two sets of devices in pairs, and during such operation draw in surplus wire from opposite ends of said sets of devices, and means for severing the stay-length in
30 two, to produce separable stay-sections for each roll of fence.
5. A wire fence machine, including two sets or series of wire connecting devices for manufacturing two widths or rolls of fence simultaneously, means for feeding a stay-wire across said sets of devices, means for severing a stay-length from said stay-wire; means for successively bringing the devices of each set into operation and for operating
35 corresponding devices of each set in pairs, and means operating after the first pair of corresponding devices of the two sets of devices begins to operate, for severing the stay-length into two stay-sections, to produce separable stay-sections for each roll of fence.
6. A wire fence machine, including two sets of wire connecting devices, the same being arranged to produce two corresponding rolls or widths of fence simultaneously, or two rolls or widths of fence of varying widths, means for feeding a single stay-wire to said two sets of devices, means for severing a stay-length from said stay-wire,
45 means for operating certain of the devices of said sets of devices in pairs to connect portions of said stay-length to wires of separate rolls and for bringing said pair of devices into action in succession, each pair
50 coming into action during the operation of another pair, and means operating after the first pair of corresponding devices of the two sets of devices begins to operate, for severing the stay-length in two, to produce separable stay-sections for each roll
55 of fence.
7. A wire fence machine, including two sets of wire connecting devices, comprising a "right series" and a "left series," the devices of both series being disposed in a line with one another; the intervals between the devices of the "right series" being less and less beginning with the innermost device of the series, and the intervals between the device of the "left series" being greater and greater beginning with the innermost device of the series, a stay-wire feed, means for severing from said stay-wire a stay-length adapted to be laid against the devices of said two sets, and a cutter operating between the innermost devices of the two sets for severing said stay-lengths in two, to produce separable stay-sections.
8. A wire fence machine, including two sets of wire connecting devices, the devices of both sets arranged in line with one another; a stay-wire feed adapted to project the stay-wire endwise transversely of said sets of devices, means for severing a stay-length from said stay-wire, means for moving said stay-length laterally and adjacent said devices, means for operating said devices to apply said stay-length to a series of wires, and a cutter for severing the stay-length intermediate the two sets of devices, for producing separable stay-sections.
9. In a wire fence machine, in combination, a coiling stem provided with a coiler head, a collar slidable on said stem, a pin attached to said collar and operable through said coiler head, a cam lever for reciprocating said collar and pin, a cam for positively moving said collar and pin in one direction, and another cam for positively moving said collar and pin in the opposite direction.
10. In a wire fence machine, in combination, two sets of aligned coilers, each set adapted to produce a distinct and separable roll of fence simultaneously, a stay-wire feed, means for severing a stay-length from said stay-wire, cutting mechanism disposed between the two sets of coilers for severing said stay-length in two separate stay-sections, and means for operating said cutting mechanism.
11. In a wire fence machine, in combination, two distinct sets of wire-coilers, the intermediate coilers of each set being loopers, whereas, the end coilers of each set are not, means for feeding a single stay-wire to said sets of coilers, means for severing a stay-length from said stay-wire, means for operating corresponding coilers of each set in coincidence and for subsequently bringing

others of said coilers in action, beginning with the loopers adjacent the inner end coilers of each set, and means for severing said stay-length in two separable stay-sections, 5 said severing means being operated approximately coincident with the operation of the inner end coilers of each set of coilers.

12. In a wire fence machine, the combination with a coiling stem provided with a 10 coiler head, of a collar slidable upon said stem, a pin attached to said collar and operable through said coiler head, a lever for

reciprocating said collar and pin, a cam for operating said lever to positively move said collar and pin in one direction, and another 15 cam to operate said lever to positively move said collar and pin in the opposite direction.

In testimony whereof I affix my signature, in presence of two witnesses.

ALVA L. KITSELMAN.

Witnesses:
